[57] **CLAIM**

The ornamental design of an adjustable patient's chair for use primarily on a hospital bed, as shown.

DESCRIPTION

FIG. 1 is a front perspective view of an adjustable patient's chair for use primarily on a hospital bed showing my design;

FIG. 2 is a left side elevational view;

FIG. 3 is a right side elevational view;

FIG. 4 is a front elevational view;

FIG. 5 is a rear elevational view;

FIG. 6 is a top plan view; and

FIG. 7 is a bottom plan view thereof.
